UNITED STATES PATENT OFFICE.

PIERRE SAMAIN, OF CUSY, FRANCE.

TUBULAR-FLOOD OR SLUICE GATE.

1,393,578.

Specification of Letters Patent.

Patented Oct. 11, 1921.

Application filed August 26, 1919. Serial No. 320,053.

To all whom it may concern:

Be it known that I, PIERRE SAMAIN, a citizen of the Republic of France, residing at Cusy, Haute-Saône, in the Republic of France, have invented certain new and useful Improvements in Tubular-Flood or Sluice Gates, of which the following is a specification.

This invention relates to improvements in 10 tubular flood or sluice gates.

By this invention the tubular gates are provided with floats, and means for varying their buoyancy and thus without having recourse to any external force the opening and 15 closing of the gate is controlled or its degree of opening is merely regulated.

In order to facilitate the operation of the gate, springs may also be employed which partially counter balance the weight of the 20 gate. The gates only comprise a single movable member, namely the tube or shaft, the weight of which with an equal discharge, is from three to six times less than that of ordinary gates. They require no adjustment 25 and do not necessitate any operating gear, the operation being done on the spot or at a distance by merely drawing water from a reservoir. The invention with reference to the accompanying drawings, shows by what 30 means the invention is put in practice.

Figure 1 is a sectional elevation through the axis of the tubular flood gate.

Fig. 2 is a plan view.

Fig. 3 shows a valve arrangement for 35 the re-admission of air into the pipe in case of a vacuum occurring.

Now referring to the Figs. 1 and 2, the gate forming a float is constituted by a tubular body 1 which is closed at its lower part 40 by a bottom 2. At the center there is a pipe 3 starting from the bottom and extending the whole height of the gate; it places the part beneath the gate in communication with the atmosphere. Two or more helical 45 springs 4 have their ends fixed to the bottom 2 of the gate and also to a cross-piece 5 by means of bolts 6 which enable the tension of the spring to be regulated. The cross-piece 5 is mounted on the reservoir wall. The 50 tension of the springs is calculated so as to keep the sluice gate open and causing an abutment fixed in the interior of the tube 3 to lie with slight pressure against the lower end of the screw 19 which is screwed into 55 the cross-piece 5 to regulate the degree of opening of the flood gate.

The interior of the gate can be placed in communication with the water of the upstream reservoir 8 by an aperture formed in a pipe 9 discharging at the side of the gate. 60

This aperture serves as a seat for a valve, the spindle of which is indicated at 10 and the end of this spindle may be attracted by an electromagnet 11 when the coil of the latter is energized by an electric current. 65

Another aperture formed in the bottom of the gate allows of the interior being placed in communication with the pipe 12 for discharging down stream and this aperture serves as a seat for a valve, the spindle 70 13 of which is controlled by an electromagnet 14. The electromagnets 11 and 14 are fixed to the tubular gate and electric wires connect them with the remote station from whence the gate is controlled. 75

The sluice gate is maintained in its rising and descending movement by lateral guides 15. The gate rests on its seat 16 by means of an annular groove 17 placed on the periphery of its base and provided with a tight 80 packing.

The working of the gate is as follows:—

The drawing shows the gate open. It is held in this position by its buoyancy and the tension of the springs which counter balance 85 its weight with a slight preponderance, the weight of the valve being also capable of being regulated by water introduced into the float.

To close the gate, electric current is transmitted to the electromagnet 11 which lifts the spindle 10 and places the interior of the float in communication with the water of the upstream reservoir and it enters the float weighting the gate 11. As the load of 95 water increases the buoyancy of the gate lessens and acts contrary to its springs so that the gate progressively descends until the annular groove 17 rests on its seat 16 and thus the valve is completely closed. By 100 switching off the current at the electromagnet 11 the valve falls on its seat and the gate remains closed.

In order to open the gate, current is transmitted to the electromagnet 14 which lifts 105 the rod 13 and its valve. The water contained in the float then runs away through the down stream pipe 12 and when the float is emptied, the gate is unloaded and the tension of the springs 4 frees it from its seat; 110 the buoyancy of the valve added by the tension of the springs, lifts it until it abuts

against the screw 19 screwed into the cross bar 5. By switching off the current at the electromagnet 14, the valve of the rod 13 falls back on its seat and the gate remains 5 open.

It is evident that this same arrangement may serve for regulating the opening of the gate by charging the float to a greater or lesser degree and thus this gate becomes a 10 means for regulating the discharge.

Thus the gate also acts automatically for holding up the water of the reservoir in case of fracture of the pipe. In case of fracture of the down stream pipe, the water 15 leaving the pipe 12 produces suction which causes a vacuum beneath the bottom of the float and the atmospheric pressure acting above, presses it down on its seat. At the same time the central pipe 3 allows of a 20 rapid entry of air into the top of the pipe and protects it for a certain time against the crushing effect of the atmospheric pressure due to the instantaneous vacuum which may be produced inside the pipe.

25 The arrangement hereinbefore described has the great advantage of not comprising any gearing. The motive force for operating the gate is provided by the water of the reservoir aided by the action of the springs, 30 the work of which is consequently very limited and there is no frictional member which dispenses with the necessity of adjustment. In addition to the pipe 3 for the admission of air into the head of the down stream pipe 35 when the gate is closed in order to complete the security there is an automatic valve added to it which is shown in Fig. 1. This valve 20 is in the form of a cup or basin to allow of a spring 21 being located therein 40 which counter-balances its weight.

In the case of vacuum in the pipe, the atmospheric pressure acts on the upper side of the valve 20 and moves the valve against the spring to allow air to pass round the 45 basin. Valves of the same kind may, if desired be suitably distributed along the pipe.

Instead of placing the valve on the pipe, it may be also placed beneath as shown in 50 Fig. 3. A spherical valve 22 resting on a seat 23 fixed to a tube 24 for the admission

of air may be employed. An arch 25 above the valve prevents the ball from escaping from its lodgment.

I declare that what I claim is:—

1. A flood or sluice gate comprising in 55 combination a tubular body closed at the bottom forming a float, communicating means between the reservoir and said float, communicating means between said float and the down stream, valves controlling the 60 flow of water in and out of said float whereby the position of said float is regulated and a tube extending from bottom to top of said tubular body to connect the underside of the float with the atmosphere. 65

2. A flood or sluice gate comprising a tubular body forming a floating valve, means of communication between the reservoir and the down stream forming a valve seating, ports in said valve whereby water 70 may enter or leave, means to regulate the position of said valve relatively to said seating by the amount of water contained in said valve, and guiding means to insure the correct vertical position of said valve relatively to its seating. 75

3. A flood or sluice gate comprising in combination a float, ports allowing the communication of the inside of the float with the reservoir and down stream respectively, 80 valves controlling said ports, means to operate said valves, a down stream channel forming a seating for said float, and means to regulate the vertical position of said float relatively to said seating. 85

4. In a flood or sluice gate the combination of a float, valve controlled ports allowing the flow of water in and out of said float electro-magnetic means to operate said valves to allow a predetermined quantity of 90 water to enter said float, and means to oppose the downward motion of said float and the water contained therein. 95

In witness whereof, I have hereunto signed my name in the presence of two sub- 95 scribing witnesses.

PIERRE SAMAIN.
